(No Model.)

E. E. BAKER.
CASE FOR TRANSFERRING TYPE.

No. 423,715.

Patented Mar. 18, 1890.

UNITED STATES PATENT OFFICE.

EDWARD EUGENE BAKER, OF PHILADELPHIA, PENNSYLVANIA.

CASE FOR TRANSFERRING TYPE.

SPECIFICATION forming part of Letters Patent No. 423,715, dated March 18, 1890.

Application filed December 7, 1889. Serial No. 332,902. (No model.)

To all whom it may concern:

Be it known that I, EDWARD EUGENE BAKER, a citizen of the United States, residing in the city and county of Philadelphia, State of Pennsylvania, have invented a new and useful Improvement in Cases for Transferring Type, which improvement is fully set forth in the following specification and accompanying drawings.

10 My invention consists of a transfer-case adapted to be removably attached to an ordinary type-distributing case for the purpose of removing type from said distributing-case into the transfer-case without commingling or confusion.

Figure 1 represents a top plan view of a transferring-case embodying my invention. Fig. 2 represents a partial side elevation and partial longitudinal section thereof on line *y y*, Fig. 1. Fig. 3 represents a transverse section on line *x x*, Fig. 1. Fig. 4 represents a similar view showing the slide of the case drawn out. Fig. 5 represents a transverse section showing the connected cases in inverted position, and also showing in dotted lines the manner of turning the cases to cause the type to pass from one to the other. Fig. 6 represents a section of a portion on line *z z*, Fig. 1. Fig. 7 represents a horizontal section on line *x' x'*, Fig. 3.

Similar letters of reference indicate corresponding parts in the several figures.

Referring to the drawings, *A* designates a distributing-case of usual construction.

35 *B* designates a transfer-case, which is adapted to be removably attached to the case *A* by catches *C*, the same being divided into compartments *D*, which coincide with the compartments in case *A*, and having on their bottoms the openings *E*. The top portion of said case *B* has a covering *F* of wire-gauze or other suitable reticulated material, so that the dust or dirt in the compartments *D* may sift therethrough, and thus be removed.

40 45 In the bottom of the case *B* is a slide or sliding plate *G*, having in a portion of the same openings or slots *H*, which align with the openings *E* in the bottom of compartments *D*, the said slide having at its end a bend *J*, for limiting the inward motion of the said slide, and a handle *K*, for convenience in operating the slide while uncovering or

covering the openings *E*. The said slide *G* is also formed with slots *L*, through which extend pins or studs *M*, whereby the outward movement of said slide is limited.

The outer wall of the casing *A* is fitted to the outer frame of the case *B* by a rabbeted joint, as at *N*, so that the cases are prevented from having lateral displacement. (See Figs. 60 3 and 4.) The walls of the compartments *D* of the case *B* are lengthened, so as to rest against the contiguous parts of the bottom of the case *B*, and thereby cause an accurate coincidence of the compartments of both 65 cases, and the said projecting walls of the compartments *D* to provide a groove on the edge of the frame of said case *B* to fit into the frame of the case *A*, and by this means the said cases are interlocked against horizontal movement, one upon the other.

When it is desired to transfer the type from case *A* to case *B*, case *B* is placed upon the case *A* and connected therewith by catches or fastenings *C*, as shown in Fig. 2. The 75 slide-plate *G* is drawn out, as shown in Figs. 4 and 5, and the two cases are overturned, as shown by dotted lines, Fig. 5, to direct the type toward the openings *E* in the compartments *D* of case *B*, and when the overturning is complete, as in Fig. 5, the type will drop from the case *A* into the compartments *D* of the case *B* and rest on the gauze covering *F*. The case *A* may now be removed from the case *B*, it being noticed that the 80 type remain in case *B*, from which they may afterward be returned into the case *A* or another case, as desired, by proper application and attachment of such case to case *B* by the manipulation of the slide and overturning of 85 the connected cases.

Having thus described my invention, what I claim as new, and desire to secure by Letters Patent, is—

1. A type-transfer case having compartments with openings therein, and a slide adapted to close said openings, formed with slots to align with the said openings, substantially as described.

2. A type-transfer case having compartments with openings therein, a distributing-case having compartments similar to the transfer-case, said distributing-case being adapted to be removably secured to said

transfer-case, and a slide formed with slots to align with the openings in said cases and adapted to open and close the same, substantially as described.

5 3. The combination of a type-transfer case having compartments with openings therein, a gauze covering therefor, a distributing-case having compartments aligning with the compartments in the transfer-case and 10 adapted to be removably attached to said transfer-case by catches, as set forth, and a

slide having an upturned edge and provided with slots to align with the openings and compartments in the said distributing and transfer cases to open and close communication between the same, substantially as described. 15

EDWARD EUGENE BAKER.
